HJALMAR NORDENMALM AND SOREN HANSSON, OF BUTLER, PENNSYLVANIA, AS
SIGNORS TO AMERICAN RAILWAY PRODUCTS CO., INC., OF NEW YORK, N. Y., A
CORPORATION OF NEW YORK.

RAILWAY HAND BRAKE.

Application filed June 10, 1925. Serial No. 36,083.

Our invention relates to a railway hand brake and particularly to a hand brake of the geared type employed to multiply the force applied by a brakeman to a brake hand 5 wheel or lever.

Brakes are now in use in which a chain drum is connected to or operable by a gear which latter meshes with a pinion operable by the brake mast. It is desirable to connect the brake member, such as the brake 10 chain, to the chain drum in such a way as to move the same rapidly to take up the slack and then more slowly, that is, with the greater force when the slack has been taken 15 up and the brakes applied.

It is an object of the invention to provide a railway brake with a simple means to rapidly take up the slack in the brake member and then wind the same up more slowly.

It is another object to provide a geared railway brake with housing means for substantially completely enclosing the gear members to protect the same from the entry 20 of foreign matter.

Other minor objects will appear as the specification proceeds.

Briefly stated, in the preferred form of the invention, we provide a frame to be secured to the car and in this frame are mounted a 30 gear for actuating a chain drum, and a pinion meshing with said gear and actuated by a hand heel or lever on the brake mast. A brake member, for example, a brake chain is connected to the chain drum in such a way 35 that it may slide radially inwardly so that when the chain drum first begins to rotate, the slack will quickly be taken up, since the point of connection is at a relatively great distance from the center of rotation and 40 when the slack has been taken up, the brake chain will then move inwardly nearer the chain drum so that further rotation thereof will permit the chain to be wound up on the chain drum with consequent exertion of 45 greater force than when the slack is being taken up. The gears, if desired, may be housed in to prevent the entry of dust, water, etc.

In the drawings which show, for illustrative purposes only, preferred forms of the 50 invention:

Fig. 1 is a top plan view in partial section of a brake embodying features of the invention;

Fig. 2 is a side elevation of parts shown 55 in Fig. 1;

Fig. 3 is a fragmentary central sectional view of the brake shown in Fig. 1;

Fig. 4 is a side elevation of a modified 60 form;

Fig. 5 is a similar view of a further modification;

Figs. 6, 7 and 8 are diagrammatic views 65 illustrating the operation of our chain drum device.

In the form shown in Figs. 1 to 3, 1 indicates a suitable frame having a yoke 2 extending therebelow. The upper side of the frame is preferably a plate 3 which forms the upper part of a housing as will be later 70 described. The yoke 2 and upper or cover plate 3 may be integrally formed and the plate 3 may have ears apertured as at 4-4 for the reception of bolts for securing the brake frame in place on a car. The plate 75 3 is bored as at 5 and the lower part of the yoke is likewise bored at 6 to receive a shaft 7 which may be in the form of a headed bolt, the head of which is received in a depression in the plate 3 and the lower end may be provided with means such as a cotter pin 8 for securing the shaft in place. The shaft 7 forms a suitable bearing for the chain drum 9 upon which the chain or other brake member is wound as will be understood. 80

In the form shown, the chain drum 9 is provided with a top plate 10 having an upstanding annular flange 11 thereon in which are formed gear teeth 12-12 forming an internal gear integrally formed with the 90 chain drum. As will be clear, the internal gear and plate 10 form a shallow cup, the upper edge of which comes quite closely to the underside of the top plate 3 of the frame and, if desired, an overhanging lip 13 may 95 be formed on the plate 3 so as to deflect dust and water out over the edge of the gear. The plate 3 and the internal gear cup thus form what may be termed a housing for the gear members whereby the latter are completely enclosed. If desired, the plate 10 may be provided with a drain aperture 14 for permitting any moisture which may accidentally get inside to drain out. 100

15 indicates a brake mast at the upper end of which there may be a hand wheel or hand lever (not shown). The lower end of the mast 15 extends through an opening in the 105

plate 3 and is secured in a pinion 16 meshing with the teeth on the internal gear previously described. If desired, the plate 3 may have a web or lug 17 for supporting the lower end of the brake mast and pinion 16.

The brake operating member, for example, a chain, is connected to the chain drum and is wound up thereon for setting the brakes on the car. We connect the brake operating member such as the chain 20 to the chain drum in such a way that the chain is drawn up quickly so as to take out the slack and then the chain slips in close to the chain drums so as to be wound up thereon and at a relatively slower speed than when the slack is being taken up.

In the particular form disclosed in Figs. 1 to 3, the lower plate 10, in this case forming a part of the internal gear, is provided with a substantially radial web or lug 18, which may carry a handle-like member or traveler 19, spaced from the flange 18 so as to permit the end link of the chain 20 to slide along on said traveler radially of the drum. In order to prevent the chain from rolling up upon itself during winding on the chain drum, we may provide a cam web 21 on the lower side of plate 10 in the form of a helical cam, so as to cause the chain to progress along axially of the chain drum as the latter rotates.

The operation will now be described by particular reference to Figs. 6, 7 and 8. The chain drum 9 is in the position shown in Fig. 6 when the brakes are off and the chain 20 will be slack. It is also to be noted that in Fig. 6 the chain 20 connects to the traveler 19 at its outer end and radially relatively far from the chain drum. Now when the chain drum 9 is rotated to the position substantially as shown in Fig. 7 the chain 20 has moved a distance substantially equal to the radius 45 extending from the center of the chain drum to the outer end of the member 19 and this during only a quarter of a revolution of the chain drum. This quarter turn quickly takes up the slack in the chain 20 and when the drum 9 is moved slightly farther than as shown in Fig. 7, the chain 20 will immediately slide inwardly on the traveler 19 so as to occupy the position as shown in Fig. 7. Further rotation then of the chain drum 55 will cause the chain to move more slowly, and still further rotation will wind the chain up on the drum 9 until with the parts as substantially shown in Fig. 8, the brakes would be applied.

It will thus be seen that by the means disclosed, the slack in the chain is taken up by a quick movement and with a relatively small rotation, say one-quarter of the turn of the chain drum. During the next half revolution the chain is wound up until the

brakes are applied. This half rotation moves the chain relatively slowly and consequently the pull on the chain is greater than when the slack is being taken up. The pull which may be put on the chain by the brakeman when the chain is near the drum as shown in Figs. 7 and 8 is of course much greater than when the slack is being taken up as shown in Fig. 6.

With the form of the invention shown in Figs 1 to 3, the gear ratio of the gear and pinion is about 4 to 1 so that one revolution of the pinion causes but a quarter of a revolution of the internal gear and consequently but a quarter of a revolution of the chain drum. This gear ratio may, of course, be changed to vary the multiplication of the force applied by the brakeman. It is to be noted, however, that with a 4 to 1 gear ratio, the slack will be substantially taken up with a quarter revolution of the chain drum or, what is the same thing, one full revolution of the brake mast.

In the form of the invention shown in Fig. 4, 25 indicates a frame to be attached to a car and this frame may carry a shaft 26 on which the chain drum 27 may be mounted. In this form, as in the previous case, the chain drum 27 may be integrally formed with the gear 28 and the flange 29 carrying the traveler 19. The brake mast 15 is secured in a pinion 29' meshing with the gear 28 and it will be observed that the mast 15 and shaft 26 are at a substantial angle to each other, say 45 degrees, and the gears 28-29 consequently are bevel gears. This construction is advantageous in that situations sometimes arise which require the brake mechanism to be placed in a relatively restricted space and this angular arrangement permits installation in such restricted space. The operation is substantially the same as that described in the previous form.

In the form shown in Fig. 5 the frame 30 carries the shaft 31 on which is mounted the chain drum 32 which in this case also may be integral with a spur gear 33 and a flange 34 carrying the handle member 19. The brake mast 15 is secured to and serves to rotate the spur pinion 34' which meshes with the spur gear 33. The operation of this form of the invention is the same as previously described. The construction shown in Fig. 5, while operating to produce substantially the same result as the form shown in Fig. 4, requires considerably more space and in some situations cannot be used for that reason.

While the invention has been described in detail and several forms shown, we do not wish to be limited to the constructions shown, since they are but illustrative and the invention may be embodied in other forms and the principles employed in various structural forms. We wish to lay particu-

lar stress, however, upon means for quickly taking up the slack in the brake operating chain and also upon the housing of the gear members to protect the same.

5 We claim:

1. In a railway hand brake, a frame, a pinion for coaction with a brake mast, a gear meshing with said pinion, a chain drum carried by said gear, a chain connection comprising a traveler on said chain drum and extending radially thereof, a brake chain having its end link mounted to slide on said traveler radially of the chain drum, whereby when the chain is at the outer end 10 of said traveler and the chain drum is rotated the chain will move rapidly to quickly take up slack and when at the inner end of said traveler will move more slowly and powerfully.

2. In a railway brake, a frame, a gear mounted on the frame and carrying a chain drum, a pinion meshing with said gear, means carried by said chain drum for receiving a brake chain, said brake chain 25 being mounted for radial movement relatively to said chain drum, whereby when the latter is rotated the brake chain may first move rapidly on a long radius and then slide inwardly radially and move slower 30 as the chain drum is rotated.

3. In a railway brake, a rotatable chain drum, means for rotating same, means for connecting a chain to said chain drum and permitting radial movement of the chain 35 relatively to said chain drum, whereby when

the chain is connected at a relatively great radial distance from the chain drum the chain will move rapidly and when the point of connection is radially inwardly the chain will move more slowly, and a cam member 40 rotatable with said drum for preventing the chain from rolling up on its connecting means.

4. In a railway brake, a frame, an internal gear mounted on said frame and having one side thereof substantially closed, a pinion meshing with said internal gear, said frame having a housing part overlapping said gears whereby the latter are substantially enclosed, a chain drum connected to said gear, one of said two last mentioned members having a radially extending flange with means to receive a chain and permit radial movement of the chain 45 thereon for the purpose described. 50

5. In a railway brake, a frame, a gear carried by said frame, a pinion meshing with said gear for operating the same, a flange on said gear and extending radially, a member carried by said flange and spaced therefrom and extending radially of the gear 55 for connection to a brake chain for the purpose described.

6. The combination defined in claim 5, and cam means for preventing the brake 60 chain connected to said gear from rolling up upon itself. 65
